UNITED STATES PATENT OFFICE.

FRIEDERICH AUGUST SCHAEFER, OF TRUCKEE, CALIFORNIA.

SLEIGH.

SPECIFICATION forming part of Letters Patent No. 506,080, dated October 3, 1893.

Application filed June 3, 1893. Serial No. 476,514. (No model.)

To all whom it may concern:

Be it known that I, FRIEDERICH AUGUST SCHAEFER, of Truckee, in the county of Nevada and State of California, have invented 5 a new and Improved Sleigh, of which the following is a full, clear, and exact description.

The invention relates to sleighs such as shown and described in the application for Letters Patent of the United States, Serial No. 10 456,888, filed by me on December 31, 1892, and allowed March 31, 1893.

The object of the present invention is to provide certain new and useful improvements, whereby the sleigh can be conveniently 15 propelled and steered over ice and snow without danger of sinking the driving wheels too deep into the snow.

The invention consists of certain parts and details and combinations of the same, as will 20 be hereinafter described and then pointed out in the claims.

Reference is to be had to the accompanying drawings, forming a part of this specification, in which similar letters of reference indicate 25 corresponding parts in all the figures.

Figure 1 is a side elevation of the improvement. Fig. 2 is a transverse section of part of the same. Fig. 3 is an enlarged transverse section of part of one of the drive wheels. 30 Fig. 4 is a side elevation of an auxiliary runner. Fig. 5 is a like view of another auxiliary runner. Fig. 6 is a cross section of the same. Fig. 7 is a cross section of the auxiliary runner shown in Fig. 4. Fig. 8 is a plan 35 view of one of the rudders. Fig. 9 is a perspective view of the mechanism for raising and lowering the drive wheels. Fig. 10 is a side elevation of a modified form of runner. Fig. 11 is an inverted plan view of the same; 40 and Fig. 12 is a cross section of the same.

The improved sleigh is provided with a platform A on the under side of which are secured comparatively flat runners B bent upward at both ends so as to permit the operator to conveniently run the sleigh forward or backward.

On the runners B may be attached auxiliary runners B', shown in Figs. 5 and 6, each being formed of a band of metal provided at one end with a hook B² adapted to hook into 50 a recess B³ formed on the forward end of the runner B, the auxiliary runner being provided at its rear end with a threaded portion

B⁴ adapted to be fastened to a boss B⁵ on the rear end of the runner B.

For running over ice or hard frozen ground 55 I provide an auxiliary runner B⁶ shown in Figs. 4 and 7, which is made of a piece of steel set edgewise and curved to the shape of the runner B, and attached thereto, similar to the runner B', by hooks and bolts at the 60 end of the said runner B⁶. Part of the sides of this runner B⁶ is flanked by longitudinally-extending strips of wood B⁷ bolted or otherwise fastened to the under side of the runner B.

On loose or wet snow it is necessary to have very wide runners B⁸, (see Figs. 10, 11 and 12) to prevent the sleigh from sinking into the snow. In order to reduce the adhesion of the wide runners B⁸ and the snow, I provide 70 the under side of the same with longitudinally-extending wires or rods B⁹ arranged parallel to each other and fastened at their ends to the curved ends of the runners B, similar to those shown in Fig. 5.

Near the forward end of the platform A are erected the posts C each connected with a rearwardly-extending beam D provided with suitable bearings for the axle E of the drive wheels F extending on the sides of the platform A below the runners, to engage the snow, ice or ground. The axle E is provided in its middle with a crank arm E' adapted to be taken hold of by the operator for turning the axle E, or connected with suitable machinery 85 located on the platform A for imparting a rotary motion to the said axle by power. Each of the driving wheels F is provided with a series of spokes F' from the outer ends of which extend on opposite sides the brackets 90 F², and these at each side are connected with each other by rings or circular bands F³, as plainly shown in Figs. 1, 2 and 3. Between the two rings are secured the paddles F⁴ extending radially and preferably toothed at 95 their outer edges, as plainly illustrated in Fig. 3. The ends of the spokes F' are connected with each other by a band or ring F⁵ which extends a suitable distance inward from the inner edges of the paddles F⁴ so that any snow or ice carried forward by the paddles, drops down onto the said band to be discharged sidewise or downward as the wheels rotate. The band or ring F⁵ also

serves to prevent the drive wheel from sinking too far into the snow. The rear ends of the bars D are guided in guideways G secured on the platform A, the said guideways being 5 provided with apertures, and a pin for locking the bars in place, as is more fully described in the application above referred to.

In order to raise or lower the drive wheels F, I provide the following device: The rear 10 ends of the bars D are pivotally-connected with downwardly and forwardly-extending arms H each provided at its lower end with a friction roller H' traveling on a fixed bearing I attached to the platform A. A cord or 15 rope J is connected with the arm H and extends rearwardly to carry at its rear end a handle J' which, when taken hold of by the operator and pulled, causes the arms H to swing rearwardly, the rollers H' traveling on 20 the bearings I, thus raising the bars D and consequently lifting the drive wheels F more or less out of the snow.

In order to steer the sleigh to the right or left, I provide the same near its forward end 25 on opposite sides with rudders K, each curved outwardly, as plainly shown in Fig. 8, and held normally out of the snow until it is desired to steer the sleigh to one side. Each rudder K is fulcrumed at K' to the side of 30 the runner B and is curved upwardly at its front end to connect with a rope or cord K² passing through the posts C and guideways G to support at the rear ends, handles K³ under the control of the operator, so that when 35 a pull is exerted on the said handles, a downward swinging motion is given to the rudders, so as to move their rear curved ends in contact with the snow or ice to steer the sleigh -to the right or left according to the left or 40 right rudder acted on by pulling the corresponding rope. A spring K⁴ connects with the rear end of each rudder K, the said spring being attached at its upper end to the corresponding post C. Thus, when the operator 45 releases the pull on the handle K³ the spring K⁴ forces the corresponding rudder back to its normal position and out of contact with the snow or ice, as illustrated in Fig. 1.

When it is desired to raise the front end 50 of the sleigh off the snow or ice, I use a set of wheels L journaled in arms L' pivoted to

the front ends of the runners the said wheels being normally folded back out of contact with the snow or ice, as explained in the application above referred to. 55

Having thus fully described my invention, I claim as new and desire to secure by Letters Patent—

1. A sleigh provided with a drive wheel comprising spokes, brackets extending from 60 the spokes, rings connecting the brackets with each other, paddles secured between the rings, and a circular band connecting the ends of the spokes with each other, the said band terminating a suitable distance from the inner edges of the said paddles, substantially as shown and described. 55

2. In a sleigh, the combination with a platform, of arms held on posts on the said platform, a drive wheel journaled in the said 70 arms, downwardly and forwardly-extending arms pivotally connected with the said journal arms of the wheel, a friction wheel held in the said last mentioned arms and adapted to roll on bearings fixed on the said platform, 75 and a rope or cord connected with the said friction wheel arms, substantially as shown and described.

3. A sleigh provided with main runners, auxiliary runners adapted to be fastened at 80 their ends to the said main runners, and longitudinal wires or rods secured to the under surface of the said auxiliary runners, substantially as shown and described.

4. The combination with the main runner 85 having a recess and boss at its respective ends, of the auxiliary runner having a hook and threaded portion at its respective ends, substantially as shown and described.

5. In a sleigh, the combination with a platform provided with runners, drive wheels held 90 vertically adjustable on the sides of the said platform, curved rudders pivoted to the front ends of the said runners, a spring connected with each of the said runners, and a cord or 95 rope connected with the said pivoted rudders and under the control of the operator, substantially as shown and described.

FRIEDERICH AUGUST SCHAEFER.
